UNITED STATES PATENT OFFICE.

FRANK H. STANARD, OF DENVER, COLORADO, ASSIGNOR TO THE STANARD AUTOMOBILE MANUFACTURING COMPANY, OF DENVER, COLORADO, A CORPORATION OF COLORADO.

STEAM-ENGINE.

1,102,102.

Specification of Letters Patent. Patented June 30, 1914.

Application filed April 8, 1913. Serial No. 759,742.

To all whom it may concern:

Be it known that I, FRANK H. STANARD, a citizen of the United States, residing at Denver, in the county of Denver and State 5 of Colorado, have invented new and useful Improvements in Steam-Engines, of which the following is a specification.

This invention relates to steam engines, the object in view being to produce an engine of the class described which is exceedingly compact and economical both in construction and operation, whereby it is especially adapted for use in automobiles, motor trucks, and mechanically propelled vehicles 15 of all kinds.

With the above and other objects in view, the invention consists in the construction, combination and arrangement of parts, as will be hereinafter more fully described, 20 illustrated in the accompanying drawings, and pointed out in the claims hereunto appended.

In the drawings: Figure 1 is a vertical longitudinal section through a steam engine embodying the present invention. Fig. 2 is a horizontal longitudinal section through the same. Fig. 3 is a vertical cross section through the engine. Fig. 4 is a detail vertical longitudinal section on the line 4—4 of 30 Fig. 2.

The engine contemplated in this invention embodies essentially a stationary frame 1, and a reciprocating body 2 supported and guided by said frame, the said frame and body being preferably inclosed by means of a jacket 3, which is shown as bolted, at 4, to the opposite ends of the stationary frame.

The reciprocating body 2 comprises a number of cylinders 5, 6, 7 and 8 radiating 40 from a common center, in which is located the single crank pin 9 of the crank shaft 10, said crank shaft being mounted in roller bearings 11 in the oppositely located central portions 12 of the stationary frame, as 45 shown in Fig. 2. In this way, a plurality of expansion chambers 13, 14, 15 and 16 is provided, the length of each of which is radial with respect to the crank pin 9, as shown in Fig. 1.

The expansion chamber 13 is constantly 50 in communication with the expansion chamber 15 by means of a by-pass 17, and the expansion chamber 14 is constantly in communication with the expansion chamber 16 55 by means of a by-pass 18. Therefore, when

steam is admitted to either of the chambers 13 and 14, it is simultaneously admitted to one or the other of the chambers 15 and 16.

19 and 20 designate stationary pistons which are rigidly connected to the stationary frame, as shown, each of said stationary pistons being provided with an inclosed steam passage 21 extending longitudinally through the same and preferably centrally thereof, as shown in Fig. 1, each of the passages 21 forming combined inlet and exhaust passages, as will hereinafter appear. The pistons 19 and 20 being stationary, the cylinders 5 and 6 work over said pistons lengthwise of the latter, the reciprocating body 2 being moved back and forth by the expansion of the steam in the expansion chambers 13 and 14.

22 and 23 designate reciprocating pistons which are mounted respectively in the expansion chambers 15 and 16, the pistons 22 and 23 being connected together, so as to work in unison, by bolts 24, the inner abutting ends of said reciprocating pistons being recessed, as shown at 26, to form a bearing for the single crank pin 9 of the crank shaft 10. The outer ends of the expansion chambers 15 and 16 are closed by plugs 27, preferably screwed therein, as shown in Fig. 1. Each of the cylinders 5 and 6 is supported and guided by one of the stationary pistons 19 and 20, as shown in Figs. 1 and 2, but it is preferred to additionally support and guide said cylinders 5 and 6 by providing the latter at diametrically opposite 90 points with flanges 28 which engage guides 29 on the stationary frame 1, as clearly shown in Fig. 2.

At a suitable point of the engine, there is arranged a steam chest 30 containing a 95 valve, the stem 31 of said valve being provided with an arm 32, to which is attached a connecting rod 33, the other end of which is pivotally attached to an arm 34 on a rock shaft 35, shown as mounted in bearings 36 and 37 on the jacket or casing 3 and the stationary frame 1, respectively. Fast on the shaft 35 is a fork 38, the arms of which carry rollers 39 which work at diametrically opposite points in contact with a cam 40 fast on the crank shaft 10. This cam is shaped as shown in Fig. 2, embodying the oppositely arranged cylindrical end portions 41 and 42 for changing the throw of the valve in the chest 30, when the fork 38 110

is slid lengthwise of the shaft 35, it being understood that said fork 38 is keyed or feathered to the shaft 35, so as to operate said shaft when the fork itself is vibrated or 5 swung by reason of the contact between the rollers 39 and the cam 40. When the fork 38 is in an intermediate position, as illustrated in Fig. 2, steam is cut off from the engine cylinders, and when said fork is slid 10 in one direction, the engine is driven ahead, and when the fork is shifted to the opposite limit of its movement, the valve is set for admitting steam to drive the engine in a reverse direction. The hub of the fork 38 is 15 provided with an annular groove 43 to receive the inturned extremity 44 of a manually operated rod 45 which projects through an opening in the jacket or casing 3, whereby said fork 38 may be shifted 20 lengthwise of the rock shaft 35 for the purpose set forth.

To adapt the engine for use on automobiles, one or more air compressing cylinders 46 and 47 may be arranged within the jacket 25 or casing 3, 48 and 49 designating pistons working in said cylinders, the piston 48 being pivotally connected, at 50, with an eccentric strap 51 passing around an eccentric 52 fast on the crank shaft 10. The other 30 piston 49 is connected pivotally, at 53, to a strap 54 passing around another eccentric 55 also fast on the shaft 10, adjacent to the eccentric 52. Air is admitted to the cylinder 46 through a check valved inlet pipe 56, 35 transferred from said cylinder to the cylinder 47 through a check valved by-pass 57, and forced from the cylinder 47 through a check valved pipe 58 to the point of use. From the steam chest 30, steam pipes 59 and 40 60 lead to opposite ends of the engine and communicate with the steam passages 21 extending centrally through the stationary pistons 19 and 20. Steam in this way is alternately admitted through the pistons 19 45 and 20 to the expansion chambers 13 and 14, and the spent steam is exhausted reversely through the same passages, the valve in the chest 30 being timed to open and close at the proper intervals to provide for the admission 50 and exhaust of the steam.

From the foregoing description, it will be seen that the steam which acts against one of the stationary pistons is also admitted to one of the other series of expansion 55 chambers, so as to operate against the reciprocating piston, the steam acting directly in one expansion chamber to force the reciprocating body in one direction, while the steam at the same time acts on the reciprocating 60 piston to drive the same lengthwise of its expansion chamber, the combined force of the two movements being applied to the common crank pin 9 of the single crank shaft 10. In this way, space is greatly economized, as the expansion chambers are 65

all arranged in a common plane, and the width of the engine need, therefore, be only sufficiently greater than the external diameters of the cylinders to provide for the frame and mounting of the working parts of the 70 engine.

What is claimed is:

1. In a steam engine, a plurality of non-rotary cylinders having a fixed relation to each other and mounted to reciprocate in a 75 body in a rectilinear path, a stationary engine frame, a rotary crank shaft journaled in said frame, oppositely located stationary pistons having a fixed relation to said frame, and oppositely located reciprocating 80 pistons having a movement in their cylinders at an angle to the movement of said cylinders.

2. In a steam engine, a stationary frame, a crank shaft journaled therein, a reciprocating body mounted in said frame and comprising series of non-rotary cylinders all movable in a body in a rectilinear path, one series being arranged lengthwise in the plane of movement of the body and another series 90 perpendicular to the plane of movement of the body, stationary pistons over which the first series of cylinders work, and reciprocating pistons working in the second series of cylinders.

3. In a steam engine, a stationary frame, a crank shaft journaled therein, a reciprocating body mounted in said frame and comprising series of non-rotary cylinders all movable in a body in a rectilinear path, one series being arranged lengthwise in the plane of movement of the body and another series 100 perpendicular to the plane of movement of the body, stationary pistons having a fixed relation to the frame and over which the first series of cylinders work, and reciprocating pistons working in the second series of cylinders, the first and second series being interconnected by by-passes.

4. In a steam engine, a stationary frame, 110 a crank shaft journaled therein, a reciprocating body mounted in said frame and comprising series of non-rotary cylinders all movable in a body in a rectilinear path, one series being arranged lengthwise in the plane 115 of movement of the body and another series perpendicular to the plane of movement of the body, stationary pistons having a fixed relation to the frame and over which the first series of cylinders work, and reciprocating pistons working in the second series of cylinders, the crank shaft having a single crank pin to which the reciprocating pistons are connected.

5. In a steam engine, a stationary frame, 125 a crank shaft journaled therein, a reciprocating body mounted in said frame and comprising series of non-rotary cylinders all movable in a body in a rectilinear path, one series being arranged lengthwise in the plane 130

of movement of the body and another series perpendicular to the plane of movement of the body, stationary pistons having a fixed relation to the frame and over which the first series of cylinders work, and reciprocating pistons working in the second series of cylinders, the first and second series being interconnected by by-passes and the stationary pistons being formed with inclosed steam

passages extending lengthwise thereof and 10 in communication with said by-passes.

In testimony whereof I affix my signature in presence of two witnesses.

FRANK H. STANARD.
